US00D793571S

(12) **United States Design Patent** (10) Patent No.: **US D793,571 S**
(45) Date of Patent: **** Aug. 1, 2017**

(54) **VIBRATOR FOR MASSAGE**

(71) Applicant: **Ievgen Iurchenko**, Kiev (UA)

(72) Inventor: **Ievgen Iurchenko**, Kiev (UA)

(**) Term: **15 Years**

(21) Appl. No.: **35/500,909**

(22) Filed: **Apr. 21, 2016**

(80) **Hague Agreement Data**

Int. Filing Date: **Apr. 21, 2016**

Int. Reg. No.: **DM/090291**

Int. Reg. Date: **Apr. 21, 2016**

Int. Reg. Pub. Date: **May 6, 2016**

(51) LOC (10) Cl. **28-03**

(52) U.S. Cl. **D24/215**

(58) **Field of Classification Search**

USPC D24/200, 215, 106, 227, 191, 214;
D14/426; 601/46; 269/3

CPC A61H 39/04; A61H 19/40

See application file for complete search history.
